(57) **CLAIM**

The ornamental design for an excavator mounted concrete handler with remote camera for accurate positioning and dispensing with hydraulic valve control, as shown and described.

DESCRIPTION

FIG. 1 is a top perspective view of an excavator mounted concrete handler with remote camera for accurate positioning and dispensing with hydraulic valve control, showing my new design;

FIG. 2 is a front view thereof;

FIG. 3 is a rear view thereof;

FIG. 4 is a left side view showing my new design;

FIG. 5 is a right side view showing my new design;

FIG. 6 is a top view showing my new design;

FIG. 7 is a bottom view showing my new design; and,

FIG. 8 is a top perspective view of the excavator mounted concrete handler with remote camera for accurate positioning and dispensing with hydraulic valve control of my new design, wherein the broken lines indicate an environment of use and form no part of the claimed design.
